UNITED STATES PATENT OFFICE.

RICHARD SMITH, OF SHERBROOKE, CANADA.

MIXING APPARATUS.

SPECIFICATION forming part of Letters Patent No. 449,259, dated March 31, 1891.

Application filed May 26, 1890. Serial No. 353,226. (No model.)

To all whom it may concern:

Be it known that I, RICHARD SMITH, a citizen of the Dominion of Canada, residing at Sherbrooke, in the county of Sherbrooke and Province of Quebec, have invented certain new and useful Improvements in Mixing Apparatus; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to apparatus for mixing or stirring either liquids or substances in a semi-liquid condition.

My invention is embodied in the peculiar relation and structural arrangement of the several elements, which together form the apparatus.

The preferred use of the apparatus is for stirring and mixing the stock of paper-pulp and the water which is introduced into the same receptacle; but of course it may be applied to many other substances and compositions.

The drawings herewith presented represent in Figure 1 a sectional elevation vertically through a mixing apparatus containing my improvements. Fig. 2 is a plan of the same reduced.

The construction of this machine is intended to be such as to combine a central feed with a circumferential discharge in order to create a thorough mixing of the matter passing through the apparatus and in process of being mixed.

In the drawings I have represented a stationary circular vessel or receptacle 1 saucer-shaped or with flaring sides, which terminate in an upright rim. This receptacle is to be bolted or otherwise firmly fastened within the vat or reservoir where it is to be employed. Further, a number of apertures 2 are cut at or near its bottom, which serve as inlet-openings to allow the liquid or semi-liquid matter in process of being mixed to enter the machine centrally at the bottom and by the relation of the several active parts to be lifted and discharged at the circumference to create

a motion like boiling, and in this way thoroughly commingle the constituents of said liquid. Centrally of said receptacle is stepped a rotary shaft 3, which is to furnish the motive power to revolve the stirrer. The latter consists of an open circular shell 4, closed at the bottom, but with feed-openings and firmly fastened to the shaft. The sides of this stirrer likewise flare, and the general cross-section corresponds with that of the fixed receptacle by which it is inclosed, but of smaller dimensions, leaving an annular passage 5 between the walls of said parts. Within this passage are located two helical blades or lifters 6, which are secured exteriorly to and revolve with the stirrer. The width of these blades is slightly less than that of the space between the fixed and revolving parts of the apparatus, and said blades wind spirally upward to the upper edge or rim of the latter, which at this point is vertical or upright. The bottom of the stirrer has several apertures or openings 8, by means of which the liquid contents can readily pass upward and enter interiorly of the stirrer from the receptacle 1, when they are influenced by the rotary motion of said stirrer and are forced upward, being discharged circumferentially from the interior of said stirrer.

It will be noticed that the stirrer is an open vessel. Moreover, since the vessel 1 and the stirrer 4 communicate by means of the apertures 8 the liquid circulation is as follows: The currents are three—a downward current exteriorly of the apparatus toward the openings 2 and a circumferential discharge created by the helical blades from the bottom upwardly through the passage 5, existing between the stationary receptacle and the rotary stirrer, while a second discharge occurs along the inside surface of said stirrer, and is created by the centrifugal effects of the liquid contents in contact therewith. As a consequence of these upward currents within the apparatus, the downward flow exteriorly of the same is directed inwardly toward the center, where it enters the apertures 2 and at once rises to be discharged circumferentially to create a boiling action, as shown and described.

The apparatus will operate as described without the blades.

What I claim is—

1. A mixing apparatus composed of a stationary receptacle or outwardly-flaring circular vessel with inlet-apertures at the bottom, a revoluble shaft centrally thereof, and a stirrer secured thereto similar in cross-section to that of the inclosing vessel, and the inlet-
15 openings connecting with the bottom of the fixed receptacle to create two currents, one within the stirrer, the other exteriorly of said stirrer and between the latter and the receptacle, substantially as herein set forth.
- 15 2. The combination, with a stationary saucer-shaped circular casing, its inlet-openings, and a similarly-shaped rotary stirrer furnished with feed-openings at the bottom,

which connect with the casing, of the lifting-blades exteriorly of the rotary stirrer, substantially as described. 20

3. The stationary flaring vessel, its bottom inlet-openings, a rotary shaft, and the revolving stirrer with flaring sides and bottom openings, combined with the helical blades exteriorly upon said stirrer, the edges of the blades being adjacent, but non-contiguous to the inclosing walls of the stationary vessel, substantially as specified. 25

In testimony whereof I affix my signature in presence of two witnesses. 30

RICHARD SMITH.
